R. B. STUCKEY

GATE FOR LEERS, OVENS, AND THE LIKE

Filed Feb. 13, 1928

UNITED STATES PATENT OFFICE.

ROBERT B. STUCKEY, OF BUCYRUS, OHIO, ASSIGNOR TO W. A. RIDDELL COMPANY, OF BUCYRUS, OHIO, A CORPORATION OF OHIO.

GATE FOR LEERS, OVENS, AND THE LIKE.

Application filed February 13, 1928. Serial No. 253,840.

My invention has for its object to provide a gate, or port, for the introduction of material into kilns, hardening cylinders, leers, and the like, wherein the material is to be treated or operated upon, while in confinement, to produce desired modifications, physical or chemical, in the material. Thus, the invention may be applied to a great variety of uses, its particular object being to provide a gate for hardening cylinders, kilns, and the like, having dimensions sufficiently large for permitting the material to be loaded on cars, or trucks, and conveyed into the construction that is closed by the gate, the gate being so formed that it may be opened by an inward movement of the gate to prevent danger of being blown or forced outward with the consequent risk to the operators of the apparatus utilizing the gate. The invention also provides means for readily securing the gate in its closed position and for swinging the gate to open it. The invention has many other features and advantages which will appear from the examination of the drawings forming a part hereof and the description hereinafter.

The invention may thus be embodied in constructions of different forms and used for a variety of purposes. To illustrate a practical application of the invention, I have selected a gate construction of a hardening cylinder as an example of the various constructions that embody the invention, and shall describe it hereinafter. The structure selected, as an example, is shown in the accompanying drawings.

Fig. 1 is a front view of the hardening cylinder head. Fig. 2 is a view of the vertical section through the cylinder head when the gate is open. Fig. 3 is a view of a section taken on the plane of the line 3—3 indicated in Fig. 1 wherein the gate is shown as closed.

Heretofore, gates have been used for opening and closing hardening cylinders for receiving cars laden with material that is to be subjected to a high pressure in the treatment of the material, as, for example, sand-lime brick. Such gates, however, are ordinarily so constructed that they are opened outward, but, as is well known in connection with such structures, there is always present the danger of blowing the gate from the cylinder. In the form of construction shown in the drawings, the gate is opened inwardly and, consequently, the cylinder may be provided with a flanged member that engages the outer surface of the gate along its peripheral edge portion and thus the gate, when in closed position, will be held against outward movement by a fixed part of the structure of the cylinder which will absolutely prevent outward movement of the gate. This will reduce the number of fastening bolts for securing the gate in its closed position and eliminate the danger of blowing out while the fastening bolts are being unfastened, since the internal pressure on the gate will automatically aid in sealing the interior of the furnace to prevent the escape of gas or steam according to the character of the process to which the material is subjected when contained within the cylinder.

In the form of construction shown in the drawings, the cylinder 1, which may be of any length, such as from 40 to 100 feet, is provided with a track 2 for receiving cars on which the material, that is to be subjected to a pressure of 50 to 100 pounds, is conveyed into or through the cylinder, whereupon the gate is closed while the material is subjected to the desired agents under the required pressure. The gate 3 is pivoted on a bracket 4 located in the head 5 of the cylinder and at a point spaced a short distance from the entering port of the head. In order that the gate 3 may be located within the head 5 of the cylinder, and in order to economize the space within the cylinder, the head 5 may be made slightly larger than the body of the cylinder. Thus, the head may be formed by a flaring rib 6 having suitable flanges for connecting the rib 6 to the sheeting that forms the body of the cylinder and to the sheeting that forms the body of the head of the cylinder. Also, a flanged rib 7 is connected to the forward edge of the sheeting that forms the body of the head of the cylinder. It has a flanged portion that extends inwardly for engaging the outer surface of the gate for efficiently sealing the gate to prevent the escape of gases or vapor. The rib 7 of the head, which forms the frame of the port, is provided with an inwardly extending ridge 8. The inner surface of the ridge 8 is provided with a channel 9. The gate 3

is provided with a peripheral ridge 16 that is adapted to fit the channel 9 and thus formed angular interfitting surfaces that coact to extend the sealing area about the 5 periphery of the gate 3. If desired, a suitable packing material 17 may be located in the channel 9 so that when the gate 3 is drawn or pressed against the frame of the port, the interior will be completely sealed 10 as against the escape of any gas or vapor that may be introduced or formed in the cylinder.

The frame 7 of the port is provided with a plurality of slotted bosses 20 that are 15 adapted to receive the bolts 21, while the gate 3 is provided with a channel 22 and a plurality of slotted bosses 23 that extend into the channel 22. The dimensions of the channel 22 are such that the heads of the 20 bolts 21 may be inserted into the slots, formed in the bosses 23 so as to engage the inner surfaces of the bosses 23 and when the nuts 24 are secured onto the ends of the bolts 21, placed in the bosses 20 and 23, the 25 gate 3 may be tightly drawn against the frame 7 of the port and thus the port will be sealed as against the escape of material.

In order that the gate 3 may be not only 30 rotatably swung into closed or into opened 35 positions and drawn into its tightly sealed position, the gate 3 is provided with a pair of brackets 30 on its inner side and the brackets 30 are provided with slots 31 in which flanged rollers 32 are located. The 40 flanged rollers 32 are rotatably supported on the rod 33 that is supported in the bracket 4 which is mounted on the inside of the head. Thus the gate 3 may be lifted from its open 45 position by swinging the gate on the rollers 32 and also the gate may be moved to its inwardly closed or sealing relation to the frame 7 of the port by drawing the gate 3 forward so that the ridge 16 will engage the packing material or enter the slot 17 when it is drawn by the nuts 21.

In order to raise the gate 3, a suitable lifting windlass may be used. The gate 3 may 50 be provided with an eye 35 that may be engaged by a hook and cable 36. The cable 55 may be passed over a suitable drum 37 that is suitably supported on the frame 7 of the port. The drum 37 may be rotated by any suitable mechanism, such as the worm wheel 38 that is operated by a suitable worm connected to a shaft 39 having the hand wheel 40 for rotating the worm, and, by reduced motion, rotating the drum 37. When the gate has been lifted by means 60 of the windlass, or other suitable mechanism, the lower end may be manually drawn into the sealing position, the lower end being shifted over the rollers 32 until the bolts 65 may be inserted in position in the slotted bosses formed integrally with the frame 7 and with the gate. Whereupon, the bolts

may be tightened down and thus the gate will be tightly sealed to close the cylinder against the escape of gases or vapor.

In order to provide for the continuation of the tracks 2, to enable the movement of 70 the cars over the gate 3 when it is in open position, rails 41 extend across its outer face and short extensions of the tracks may be located intermediate the ends of the rails 41 and the tracks 2, located within the cylinder, and the tracks that lead up to the entrance or port of the cylinder. These 75 replaceable parts may be secured in any suitable manner in order that the cars may be moved into and out of the cylinder, or, if desired, through the opposite end of the cylinder which would be, preferably, constructed in a similar manner that the head, described above and illustrated in the drawings, is constructed.

I claim:

1. A gate for hardening cylinders and the like, comprising a movable gate member, means for pivotally and slidably supporting one end of the gate member and located on the inside of the cylinder, a frame for engaging the outside of the gate member, and means for drawing the gate member against the frame.

2. In a gate for hardening cylinders and the like, a movable gate member located on the inside of the cylinder and having a channel, a frame for engaging the outside face of the gate exterior to the channel, the gate member and the frame having substantially registering slotted bosses, and bolts located in the slotted bosses for drawing the gate member against the frame.

3. In a gate member for hardening cylinders and the like, a movable gate member located on the inside of the cylinder, a flanged member for engaging the outside face of the gate, the gate member and the flanged members having registering channels and ridges for sealing the interior of the cylinder, and means for drawing the gate member against the flanged member.

4. A gate for hardening cylinders and the like, comprising a movable gate member, means for pivotally and slidably supporting one end of the gate member and located on the inside of the cylinder, a frame for engaging the outside of the gate member, the gate member having a slot, and the frame and the gate member having slotted bosses and bolts interconnecting the slotted bosses for drawing the gate member against the frame.

5. In a gate member for hardening cylinders and the like, comprising a movable gate member, means for pivotally supporting one end of the gate member, rail tracks located on the face of the gate member, and means for lowering the gate member to a substantially horizontal position.

6. A gate member for hardening cylinders and the like, a cylinder having rail tracks, a movable gate member for closing the cylinder and having tracks on its outside surface adapted to register with the tracks in the cylinder when the cylinder is opened, the cylinder having a flanged member for engaging the face of the gate member when the cylinder is closed, the gate member having a channel, the flanged member having slotted bosses and the gate member having slotted bosses located in the channel and registering with the slotted bosses of the flanged member, and bolts for drawing the gate member against the flanged member when the cylinder is closed. 15
- 10 7. A gate member for hardening cylinders and the like, a cylinder having rail tracks, a movable gate member for closing the cylinder and having tracks on its outside surface adapted to register with the tracks in the cylinder when the cylinder is opened, the cylinder having a flanged member for engaging the face of the gate member when the cylinder is closed, the gate member having a channel, the flanged member having slotted bosses and the gate member having slotted bosses located in the channel and registering with the slotted bosses of the flanged member, and bolts for drawing the gate member against the flanged member when the cylinder is closed. 20
- 25

In witness whereof I have hereunto signed my name to this specification.

ROBERT B. STUCKEY.
